UNITED STATES PATENT OFFICE.

ALMA KAUTZSCH, OF PHILADELPHIA, PENNSYLVANIA.

CORSET CLASP.

Application filed August 25, 1926. Serial No. 131,365.

The invention stated in its broadest terms relates to corsets and has more especial relation to a clasp therefor.

The leading object of the present invention is to provide a corset clasp which is of simple, unexpensive and efficient structure having such interlocking parts as shall tend to reduce to a minimum, the possibility of clasp separation during a period of corset wear.

Other and further objects reside in the provision of general details of construction and arrangement of parts for attaining the results sought by said leading object.

15 The invention consists of the novel construction hereinafter described and finally claimed.

20 The nature, characteristic features and scope of the invention will be more fully understood from the following description taken in connection with the accompanying drawings forming part hereof, and in which:

25 Fig. 1 is a view in front elevation of a corset with the corset fabric broken to illustrate clasp structure.

Fig. 2 is a view in front elevation, upon an enlarged scale, illustrating details of clasp construction.

30 Fig. 3 is a view in cross-section taken upon the line 3—3 of Fig. 2.

Fig. 4 is a face view of the base-plate as shown in said foregoing figures.

Fig. 5 is an edge view of Fig. 4.

Fig. 6 is a face view of the clamp, shown 35 in Figs. 2 and 3, and

Fig. 7 is a detail view hereinafter referred to.

40 For the purpose of illustrating my invention, I have shown in the accompanying drawings, one form thereof which is at present preferred by me, since the same has been found in practice to give satisfactory and reliable results, although it is to be understood that the various instrumentalities of 45 which my invention consists can be variously arranged and organized and that my invention is not limited to the precise arrangement and organization of the instrumentalities as herein shown and described.

50 In the drawings the reference numeral 1 designates a corset of any desired shape and style the front parts of which are adapted to be secured along the median line 2 by a plurality of securing mediums. Heretofore fasteners comprising studs and slotted catches have been employed which have the

tendency to separate or become detached during body movements of the wearer of the corset. Along one edge of the corset there is attached a plurality of metal plates 3, slotted at 4 and apertured at 5 so that the plates may be sewn to the corset, said plates, which are thin, flat and elongated, may be of any desired number. Secured to the opposite edge of the corset are a series of companion parts for interlocking relation with respect to said plates. Said parts each comprise a thin, flat plate 6, apertured at 7, for being sewn to the corset 2. Each plate 6, has struck up therefrom a pair of lugs 8 having 60 apertures for pivotally receiving the pintles 9 of a clamp 10. The clamp 10 is formed upon an arc of a circle as shown in Fig. 3 and is provided with a finger piece 11. In alignment with the lugs 8 and secured to 65 plate 6 as at 12 beneath clamp 10, is a spring 13.

70 In use the two edges of the corset are drawn around the body of the wearer and the clamps 10 inserted through the slots 4 of plates 3. The clamps 10 are then 75 "snapped" down upon the plates 6, against the pressure of springs 13, thus providing an efficient and reliable interlock of parts which are relatively difficult to accidentally 80 misplace. The finger piece 11 is useful in unfastening the clasp parts. In practice the goods of which the corset is covered may be 85 employed to conceal the metal parts.

90 It will now be apparent that I have devised a novel and useful construction of 95 corset clasp which embodies the features of advantage enumerated as desirable in the statement of the invention and the above description and while I have in the present 100 instance shown and described the preferred embodiment thereof which has been found in practice to give satisfactory and reliable results, it is to be understood that the same is susceptible of modification in various particulars without departing from the spirit or scope of the invention or sacrificing any 105 of its advantages.

What I claim is:—

110 In a corset opening upon a front vertical medial line, the combination of a plurality of thin flat, elongated plates secured adjacent to one vertical edge of the corset each plate having a spring pressed, elongated clamp pivotally mounted thereon, provided with a finger piece, a leaf spring for each pivotal clamp arranged in alignment with

the pivot points, said leaf spring being elongated and riveted intermediate of its ends to said plate in a plane below the said pivotal clamp and substantially in alignment 5 with the axis of the latter, portions of said spring on each side of the riveted portion being bowed upwardly to contact with the inner pivotal edge of said clamp, and a plurality of other thin, flat and slotted plates 10 secured to the opposite vertical edge of the

corset, said pivotal clamps being co-extensive with the slotted plates throughout the major portion of their extent and each clamp being adapted to penetrate said slotted plates and to be moved about their pivot points for 15 clamping upon said first mentioned plates to interlock said corset front.

In testimony whereof, I have hereunto signed my name.

ALMA KAUTZSCH.
